CLAIM

The ornamental design for a diaper bag with a changing station as shown and described.

DESCRIPTION

FIG. 1 is a front, right and top perspective view of a diaper bag with a changing station showing my new design;

FIG. 2 is a rear, left and bottom perspective view thereof;

FIG. 3 is a front elevational view thereof;

FIG. 4 is a rear elevational view thereof;

FIG. 5 is a left view thereof;

FIG. 6 is a right view thereof;

FIG. 7 is a top plan view thereof;

FIG. 8 is a bottom plan view thereof; and,

FIG. 9 is an enlarged view of a portion labeled as 9 on FIG. 1.

The shorter broken lines illustrate portions of the diaper bag with a changing station that form no part of the claimed design. The longer broken lines circumscribe enlarged detail.
